(57) **CLAIM**

We claim the ornamental design for blower housing, as shown and described.

DESCRIPTION

FIG. 1 is a perspective view of an embodiment of a blower housing;

FIG. 2 is a top view of the blower housing of FIG. 1;
FIG. 3 is a bottom view of the blower housing of FIG. 1;
FIG. 4 is a right side view of the blower housing of FIG. 1;
FIG. 5 is a left side view of the blower housing of FIG. 1;
FIG. 6 is a front view of the blower housing of FIG. 1;
FIG. 7 is a back view of the blower housing of FIG. 1;
FIG. 8 is a perspective view of another embodiment of a blower housing;

FIG. 9 is a top view of the blower housing of FIG. 8;
FIG. 10 is a bottom view of the blower housing of FIG. 8;
FIG. 11 is a right side view of the blower housing of FIG. 8;

FIG. 12 is a left side view of the blower housing of FIG. 8;
FIG. 13 is a front view of the blower housing of FIG. 8; and,
FIG. 14 is a back view of the blower housing of FIG. 8.
In the drawing, the broken lines depict unclaimed environmental subject matter only and form no part of the claimed design.
